(57) **CLAIM**

We claim the ornamental design for an automotive bull bar, as shown and described.

DESCRIPTION

FIG. 1 is a top, front, and right side perspective view of an automotive bull bar showing my new design in accordance to a first embodiment;

FIG. 2 is a right side elevation view thereof;

FIG. 3 is a front elevation view thereof;

FIG. 4 is a left side elevation view thereof;

FIG. 5 is a rear elevation view thereof;

FIG. 6 is a top plan view thereof;

FIG. 7 is a bottom plan view thereof; and

FIG. 8 is a perspective view thereof as installed on the front of a motor vehicle.

FIG. 9 is a top, front, and right side perspective view of an automotive bull bar showing my new design in accordance to a second embodiment;

FIG. 10 is a right side elevation view thereof;

FIG. 11 is a front elevation view thereof;

FIG. 12 is a left side elevation view thereof;

FIG. 13 is a rear elevation view thereof;

FIG. 14 is a top plan view thereof;

FIG. 15 is a bottom plan view thereof; and

FIG. 16 is a perspective view thereof as installed on the front of a motor vehicle.

FIG. 17 is a top, front, and right side perspective view of an automotive bull bar showing my new design in accordance to a third embodiment;

FIG. 18 is a right side elevation view thereof;

FIG. 19 is a front elevation view thereof;

FIG. 20 is a left side elevation view thereof;

FIG. 21 is a rear elevation view thereof;

FIG. 22 is a top plan view thereof;

FIG. 23 is a bottom plan view thereof; and,

FIG. 24 is a perspective view thereof as installed on the front of a motor vehicle.

The broken line showing of the motor vehicle is provided for the purpose of illustrating environmental structure and forms no part of the claimed design.
